United States Patent Office

Des. 233,980
Patented Dec. 24, 1974

233,980

BOTTLE

Donald George Watt, Toronto, Ontario, Canada, assignor
to Societe d'Assistance Technique pour Produits Nestle
S.A., Lausanne, Switzerland

Filed Mar. 2, 1973, Ser. No. 337,679

Term of patent 14 years

Int. Cl. D9—01

U.S. Cl. D9—115

FIG. 2

FIG. 1

FIG. 4

FIG. 3

FIG. 1 is an elevational view of a bottle embodying my new design, the sides not shown being the same in appearance as the side shown;

FIG. 2 is a top plan view thereof;

FIG. 3 is a bottom plan view thereof; and

FIG. 4 is a sectional view taken along line 4—4 of FIG. 1.

I claim:

The ornamental design for a bottle, as shown and described.
